UNITED STATES PATENT OFFICE.

SAMUEL K. LOWMAN, OF HAGERSTOWN, MARYLAND, ASSIGNOR TO JONES COLD STORE DOOR CO., OF HAGERSTOWN, MARYLAND, A CORPORATION OF MARYLAND.

REGISTERING APPARATUS.

No. 870,975.

Specification of Letters Patent.

Patented Nov. 12, 1907.

Application filed June 22, 1907. Serial No. 380,351.

To all whom it may concern:

Be it known that I, SAMUEL K. LOWMAN, a citizen of the United States, residing at Hagerstown, in the county of Washington and State of Maryland, have 5 invented new and useful Improvements in Registering Apparatus, of which the following is a specification.

This invention relates to a registering apparatus.

An apparatus involving my invention may be used with advantage in various connections, although the 10 same is of particular utility when employed in connection with a storage room into which ice is delivered.

In the drawings accompanying and forming a part of this specification I show in detail one effective form of embodiment of the invention which, to enable those 15 skilled in the art to practice the same, will be set forth at length in the following description, while the novelty of the invention will be included in the claims succeeding said description. In said embodiment the apparatus is shown in connection with a storage room and 20 it is of such a character as to effect a register or count of blocks of ice delivered thereto.

The apparatus is simple in construction, can be inexpensively and easily made, and can be connected with storage rooms or houses without any material modification thereof.

Referring to said drawings: Figure 1 is a cross sectional view of the entering portion or doorway of an ice storage room equipped with registering apparatus involving my invention. Fig. 2 is a horizontal section 30 on line 2—2 of the same. Fig. 3 is a perspective view on an enlarged scale of the registering apparatus, and Fig. 4 is a like view on an enlarged scale of a sleeve or boxing.

Like characters refer to like parts throughout the several figures of the drawings.

In Figs. 1 and 2 I have illustrated the doorway leading into an ice storage room, the same being denoted in a general way by 5 and having a door as 6 mounted therein, the door 6 being adapted to be opened by the 40 impact of blocks of ice thereagainst and to be closed by the action of a spring as 7 acting thereagainst. The front of the storage room is denoted by 8. These features in themselves form no specific part of the invention, for which reason they need not be further described. I prefer to make the bottom 9 of the doorway 45 downwardly and inwardly inclined to facilitate the passage of ice into the storage room or compartment. The bottom usually comprises a wooden body provided with a facing as 10 of sheet metal, which facing protects the wooden body from wear. At the entering end of the doorway and naturally at the outer end of the inclined bottom 9 is a ledge or shoulder 11 extending partially across the said doorway, and the purpose of this ledge or shoulder is to break or separate cakes of ice in

case they should adhere, by virtue of which such cakes 55 of ice individually operate the registering mechanism. Were several cakes to stick together, such cakes in such condition might effect but a single operation of the register, whereas, if they are broken up in case there is any adherence thereof, I can obtain a proper count of 60 the same. The inclined bottom 9 serves as a run-way along which the cakes of ice travel toward the interior of the storage room.

There is shown as mounted in an opening in the bottom or inclined run-way 9 between the front and the 65 rear ends thereof a sleeve or boxing 12, the upper edge of which is represented as flush with the upper surface of the said bottom or run-way 9. This sleeve or boxing 12 incloses for vertical reciprocation the block 12 which is operated by the cakes of ice to effect the action of a 70 register such as 14 suitably mounted on the front 8. This boxing or sleeve 12 is shown as having lateral lugs 15 adapted to be suitably attached to the under side of the bottom 9 and as also having a cross-bar as 16 through a central perforation in which the depending 75 stem 17 of the block 13 is adapted to vertically move.

The stem 17 is shown as jointed or pivoted at its lower end to one end of a lever as 18, the opposite end of said lever being similarly connected to a rod as 19 vertically disposed and equipped with a weight as 20 80 which, if desired, may be adjustably mounted on the rod and held in an adjusted position thereon by means of the set-screw 21. The lever 18 is shown as fulcrumed between its ends to a bracket as 22 attached suitably to the under side of the bottom 9.

The lower end of the vertical rod 19 is connected with the lever 18, while the upper end of said rod is jointed to one end of a lever as 23, the opposite end of said lever being connected to one end of a rod or link as 24. The lever 23 is pivotally supported between its ends 90 on one of the sides of the doorway 5. The forward end of the rod or link is connected with the crank-arm 25 connected operatively with the register 14 so that, when the arm 25 is swung forward, said register will be operated.

The weight 20 serves as an effective and positive means for upholding the block 13 normally in its operative position, the top of said block at this time being above the upper surface of the run-way or bottom 9, as clearly shown in Fig. 1. The block is in proximity 100 to the shoulder 11, by virtue of which the shoulder will insure the passage of the cakes of ice successively on to said block 13. Each cake of ice when it passes free of the ledge or shoulder 11, will depress the block or bring its upper surface flush with the corresponding portion 105 of the bottom or run-way 9. As the block 13 is lowered in such manner the rod 19, through the intermediate lever 18, is elevated, whereby the rod 24, through the

action of the lever 23, will be thrust forward to swing the arm 25 forward and cause the operation of the register 14 in the manner previously set forth. As soon as a cake of ice passes from off the block 13 the weight 5 20 by dropping can, through the intervening parts, return the arm 25 and the block 13 to their original positions. In the present case there is but one block 13 in connection with the run-way or inclined bottom 9. It will be seen that the upper surface of this inclined 10 run-way is smooth so as to provide for the proper passage of the separated cakes of ice therealong.

What I claim is:

1. The combination of an inclined run-way having a ledge at the front side of the same to break adhering cakes 15 of ice, a single block, the upper surface of which is normally located above the corresponding portion of said run-way and said corresponding portion being smooth, said

block being operable by the individual cakes of ice, a register, and connections between the block and the register for operating the latter. 20

2. The combination of a run-way, a sleeve mounted in the run-way, a block movable in said sleeve and having a stem, the sleeve being provided with a perforated cross-bar through the perforation in which said stem is movable, a lever connected with the stem, a rod connected with and operable by the lever, said rod having a weight connected therewith, a second lever to which said rod is connected, a second rod connected with the second lever, and a register provided with an operating arm to which said second rod is connected. 25

In testimony whereof I have hereunto set my hand in presence of two subscribing witnesses. 30

SAMUEL K. LOWMAN.
